(57) **CLAIM**

I claim the ornamental design for a bunion toe spacer, as shown and described.

DESCRIPTION

FIG. 1 is a perspective view of a bunion toe spacer according to my design.

FIG. 2 is a top plan view thereof. The bottom plan view is a mirror image of the top plan view.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an in-use view thereof; and,

FIG. 8 is an in-use view thereof.

The broken lines in the drawings depict environment and form no part of the claimed design.
